Primary Examiner — Angela J Lee*Assistant Examiner* — Liv C Anderson(74) *Attorney, Agent, or Firm* — Daniel M. Cohn;
Howard M. Cohn(57) **CLAIM**

The ornamental design for a lash light for eyelash extension as shown and described.

DESCRIPTION

FIG. 1 is a perspective view of a lash light for eyelash extension showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 1;

FIG. 11 is a partial enlarged view of portion 11 in FIG. 2;

FIG. 12 is a partial enlarged view of portion 12 in FIG. 2; and,

FIG. 13 is a partial enlarged view of portion 13 in FIG. 2. The broken lines depict portions of the lash light for eyelash extension and form no part of the claimed design.
